CIRCUIT INTERRUPTER FOR HIGH-TENSION OVERHEAD WIRES

Filed Sept. 13, 1950

Fig. 1.

UNITED STATES PATENT OFFICE

2,543,596

CIRCUIT INTERRUPTER FOR HIGH-TENSION OVERHEAD WIRES

John M. Penn, Orangeburg, S. C.

Application September 13, 1950, Serial No. 184,614

5 Claims. (Cl. 175—294)

1

This invention relates to an attachment for use with high tension overhead wires for automatically cutting and deenergizing the wire in the event that the wire becomes disengaged from its support or its support is knocked down or broken off, so that the wire will be deenergized before it can drop to a level to afford a human hazard, to thereby eliminate deaths which are commonly caused by high tension wires which are allowed to drop to positions on or adjacent the ground due to storms or other causes which tear the wires loose from their supports or break off the supports.

More particularly, it is an aim of the present invention to provide an electrically energized severing unit which is adapted to be connected to a high tension wire for receiving current therefrom for energizing the unit only when the wire is displaced downwardly relative to its normal position for thereby automatically severing the wire to de-energize it before the wire can drop to a level at which it would provide a human hazard.

Various other objects and advantages of the invention will hereinafter become more fully apparent from the following description of the drawing, illustrating a presently preferred embodiment thereof, and wherein:

Figure 1 is a perspective view showing the invention in an applied position;

Figure 2 is a sectional view thereof taken substantially along a plane as indicated by the line 2—2 of Figure 3, and

Figure 3 is a top plan view of the invention.

Referring more specifically to the drawing, for the purpose of illustrating a preferred application and use of the circuit interruptor for high tension wires, comprising the invention and designated generally 5, the upper end of an electric pole 6 is illustrated in Figure 1 having the usual cross-arm 7 secured thereto, one end only of which is shown projecting laterally from the pole 6 near its upper end. Said end of the crossarm 7 is shown provided with a conventional up-standing electrical insulator 8 to which a portion of a high tension wire 9 is connected in a conventional manner and so that the conductor 9 will extend transversely over said end of the crossarm 7 without being in contact therewith. The parts 6 to 9, inclusive illustrate a conventional mounting for a high tension wire.

The circuit interrupter 5 includes an electromagnet, designated generally 10 inclosed within a housing 11 which is preferably formed of an electrical insulating material and which is pro-

2

vided with a plurality of outwardly projecting apertured ears 12 for receiving suitable driven fastenings 13 by means of which the housing 11 is secured to one side of the crossarm 7, inwardly of but adjacent the high tension wire 9. The housing 11 includes the usual coil of wire 14 and the usual core 15 which is disposed within the coiled wire 14 and energized by current passing through said wire. An arm 16 is fixed to 10 and projects outwardly from the housing 11, adjacent its upper end and extends in a direction substantially parallel to the crossarm 7 and extends outwardly to beyond the high tension wire 9. The arm 16, adjacent its inner end is 15 provided with a portion 17 of electrical insulating material for positively insulating the arm 16 from the housing 11 but which may be omitted if the housing is formed of electrical insulating material. The arm 16 is provided with 20 a downwardly offset arcuate intermediate portion 18, over which a portion of the high tension wire 9 extends and said portion 18 is preferably provided with an upwardly opening longitudinally extending groove or channel 19. A lever 20 has 25 one end pivotally connected as seen at 21 to the outer end of the arm 16 and extends inwardly and upwardly therefrom, relatively to said arm 16 and to the electromagnet 10. An armature 22 is secured to the inner end of the lever 20, which constitutes its free end, and is disposed 30 directly over the upper end of the core 15. The lever 20 is provided with a portion 23 formed of electrical insulating material at its inner end and which connects with the armature 22 for insulating the lever 20 from the armature 22. The lever 20 is provided with an integral blade 24 which projects downwardly therefrom above the arcuate arm portion 18 and which extends longitudinally of the lever 20 and has an arcuate 35 convexly bowed bottom cutting edge which is disposed over and normally spaced from the arcuate portion 18 and which is receivable into the groove 19 when the lever 20 is swung downwardly on its pivot 21, as will hereinafter be described. The high tension wire 9 has a portion extending 40 between the arcuate portion 18 and the cutting edge of the blade 24. A leaf spring 25 is secured by a fastening 26 at one of its ends to the underside of the lever 20, near the free end of said lever, and extends longitudinally of the lever and is curved toward the arm 16 and has its opposite, free end slidably bearing upon the arm 16 for supporting the lever 20 and armature 22 in their elevated positions as illustrated in Figure 1 and 45 in full lines in Figure 2.

An electrical conductor 27 has one end thereof connected by a post 28 of electrical conducting material through the housing 11 to one end of the coil of wire 14 and the opposite end of the conductor 27 is connected to the high tension wire 9 between the end thereof, not shown, which is connected to the source of current and the insulator 8; the arm 16 and lever 20 being disposed on the other side of the insulator 8 to the point of connection of the conductor 27 with the wire 9. A suitable resistance 29 is interposed in the conductor 27 to reduce the current supplied to the electromagnet 10. A post 30 of electrical conducting material is connected to the opposite end of the coiled wire 14 and extends outwardly through the housing 11 and is connected to one end of a conductor wire 31, the opposite end of which is connected to a stationary switch contact 32 which is suitably secured to the housing 11 and which is suitably insulated from said housing, if the housing is formed of electrical conducting material. A movable switch contact comprises a resilient strip of electrical conducting material 33 having an upper end which is secured by a fastening 33a to the housing above the contact 32 and is suitably insulated from the housing, if the latter is formed of electrical conducting material. The lower, free end of the resilient contact strip 33, which is spaced outwardly from the housing 11, is yieldably retained by its resiliency out of engagement with the contact 32, as seen in Figure 2. A lever or arm 34, preferably of electrical insulating material is connected at one end thereof by a hinge 35 to the arm 16 and is hingedly supported thereby for vertical swinging movement. The lever 34 extends transversely across the upper part of the movable switch contact 33 and is disposed above its lower free end. Said lever 34 is provided at its opposite end with a lateral extension 36 having a forked or bifurcated outer free end 37 including upper and lower furcations or prongs which straddle a portion of the high tension wire 9 and so that the upper prong or furcation rests upon and is supported by the wire 9 for thereby supporting the lever 34 in an elevated position above and out of engagement with the movable contact 33. An electrical conductor or ground wire 38 has one end connected to the movable switch contact 33 and the opposite end of said wire 38 is suitably grounded as indicated at 39.

It will be readily apparent that the circuit interruptor 5 may be mounted on the crossarm of each pole 6 along a line of supporting poles and crossarms which support a high tension wire or the unit 5 may be mounted on crossarms of alternate poles or at any other desired distance apart. Likewise, if another high tension wire, not shown, is supported on the opposite end of the crossarm 7, not shown, a corresponding unit could be provided for this high tension wire. So long as the high tension wire 9 is properly supported at spaced intervals by insulators 8 which are supported on crossarms 7, the wire 9 by engagement with the upper prong or furcation of the fork 37 will support the lever 34 in an elevated position out of engagement with the movable contact 33 so that the electromagnet 10 will not be grounded by engagement of contacts 32 and 33 and therefore no current will flow through the winding 14 thereof. However, if a pole 6 located beyond the lower right-hand end of the wire as shown in Figure 1 is broken off or uprooted or if a crossarm 7 thereof is broken, to permit the lower right-hand end of the wire 9 to drop downwardly, this will result in the wire 9 between its lower

right-hand end and the insulator 8 moving out of engagement with the upper prong or furcation of the fork 37 to permit the lever 34 to swing downwardly to momentarily engage and displace the lower free end of the movable switch contact 33 into engagement with the stationary contact 32 so that the electromagnet 10 will be grounded through the conductor wire 31, stationary contact 32, movable contact 33, and conductor 38 to the ground 39 so that current can then flow from the high tension wire 9 through the conductor 27 to the winding 14 of the electromagnet for energizing the core 15. This will attract the armature 22 which will be drawn downwardly and into engagement with the core 15, as indicated in dotted lines in Figure 2, for swinging the lever 20 downwardly against the action of its spring 26. When this occurs, the convex cutting edge 41 of the knife or blade 24 will initially force the wire 9 down against the upper grooved surface of the downwardly bowed arm portion 18 and will thereafter sever said wire portion as the cutting edge 41 moves into the groove 19 to thus de-energize the high tension wire 9 so that the portion thereof which has been allowed to drop downwardly to a position adjacent the ground will not be energized and therefore will not provide a hazard. It will be readily apparent that this de-energizing of the high tension wire will be accomplished almost instantaneously whenever the wire drops appreciably below its normal level so that regardless of the cause, the high tension wire will be de-energized before it can drop to a level where it will be dangerous to persons standing on the ground. The lever or arm 34 will move past the lower end of the contact 33 in its downward swinging movement so that contact 33 will almost immediately move out of engagement with the contact 32 to again de-energize the electromagnet; however, the electromagnet will be energized long enough to accomplish cutting of the wire as heretofore described.

Various modifications and changes are contemplated and may obviously be resorted to, without departing from the spirit or scope of the invention as hereinafter defined by the appended claims.

I claim as my invention:

1. A circuit interruptor for high tension wires comprising an arm across which a high tension wire is adapted to extend and over which a portion of the high tension wire is disposed, a lever pivotally connected at one end to one end of said arm, a blade depending from said lever and having a cutting edge extending longitudinally thereof and disposed over said portion of the high tension wire, electromagnetic means adapted to be supported by a crossarm of an electric pole to which the opposite end of said arm is secured and from which said arm is insulated, an armature connected to and insulated from the opposite end of the lever and disposed over and normally spaced from said electromagnetic means, a stationary switch contact supported by and electrically connected to one end of the winding of said electromagnetic means, a grounded movable contact having an upper end connected to and insulated from the electromagnet and an outwardly offset lower end disposed for yielding movement into engagement with the stationary contact, a second lever pivotally connected at one end to the arm for vertical swinging movement thereon having a portion resting on the high tension wire and supported thereby for supporting an intermediate portion of the second lever

above and adjacent the lower free end of the movable contact and out of engagement therewith, said second lever being displaced downwardly by gravity when the portion of the high tension wire engaged by the second lever is displaced downwardly a predetermined distance to momentarily engage the movable contact and displace it into engagement with the stationary switch contact for momentarily grounding said electromagnetic means, and an electrical conductor connecting the opposite end of the winding of the electromagnetic means to the high tension wire remote to said last mentioned portion of the wire for energizing the electromagnetic means when the stationary and movable switch contacts are in a circuit making position to attract the armature downwardly for causing the blade to cut through the first mentioned portion of the wire to de-energize the high tension wire.

2. A circuit interruptor as in claim 1, and spring means engaging adjacent sides of the arm and first mentioned lever and normally supporting the first mentioned lever and armature in elevated positions relatively to said electromagnetic means.

3. A circuit interruptor for high tension wires comprising shear means between which a portion of a high tension wire is adapted to extend, said shear means including a stationary part and a movable part, an electromagnet adapted to be supported on a crossarm of an electric pole and adapted to be electrically connected to the high tension wire on one side of said shear means, an armature supported by and insulated from the movable shear part and normally disposed in spaced relationship to the electromagnet, a switch including a stationary contact connected to the electromagnet and a grounded movable resilient contact normally retained by its resiliency out of engagement with the stationary contact, and a lever pivoted to the stationary shear part for vertical swinging movement having a portion engaging the high tension wire on the other side of said shear means and normally supported thereby above and out of engagement with the movable contact, said lever being gravity urged

into engagement with the movable contact to displace said contact into engagement with the stationary contact whereby the electromagnet is grounded and energized when the last mentioned portion of the high tension wire is displaced downwardly a predetermined distance to thereby cause the armature to be attracted by the electromagnet for actuating the shear means for severing the first mentioned portion of the high tension wire.

5. A circuit interrupter as in claim 3, and spring means interposed between the stationary part and movable part of said shear means and normally urging said parts away from one another and for supporting said armature in spaced apart relationship to the electromagnet.

15 4. A circuit interrupter as in claim 3, and spring means interposed between the stationary part and movable part of said shear means and normally urging said parts away from one another and for supporting said armature in spaced apart relationship to the electromagnet.

5. A circuit interrupter as in claim 3, said movable contact having a free end normally disposed beneath and in the path of downward swinging 20 movement of the lever and engaged by the lever when the latter is swung downwardly for momentarily displacing the movable contact into engagement with the stationary contact for completing the electric circuit to the electromagnet,

25 25. A circuit interrupter as in claim 3, said movable contact having a free end normally disposed beneath and in the path of downward swinging movement of the lever and engaged by the lever when the latter is swung downwardly for momentarily displacing the movable contact into engagement with the stationary contact for completing the electric circuit to the electromagnet,

30 30. said lever being movable past the free end of the movable contact to release said movable contact to permit the movable contact to be biased by its resiliency out of engagement with the stationary contact whereby the electric circuit to the electromagnet is only momentarily maintained in a closed position.
